INVENTOR.

Julia H. Auerbach

BY

R. S. Berry,

ATTORNEY.

UNITED STATES PATENT OFFICE.

JULIA H. AUERBACH, OF LOS ANGELES, CALIFORNIA.

CORSET-FASTENING.

1,351,728.

Specification of Letters Patent. Patented Sept. 7, 1920.

Application filed May 27, 1918. Serial No. 236,666.

To all whom it may concern:

Be it known that I, JULIA H. AUERBACH, a citizen of the United States, residing at Los Angeles, in the county of Los Angeles and State of California, have invented a new and useful Corset-Fastening, of which the following is a specification.

This invention relates to a garment fastener and particularly pertains to a lacing for corsets and the like. It is the object of this invention to provide a means for lacing corsets or other garments whereby the use of narrow lacings and numerous eyelets may be dispensed with and broad ribbons with few engaging members employed in lieu thereof.

Another object is to provide a device whereby a lacing ribbon may be connected to the contiguous edges of a garment to be laced together at opposite points with overlapping strands of the ribbon substantially in alinement with each other with the terminals of the ribbon extending in opposite directions and adapted on being pulled in opposite directions to draw the edges of the garment toward each other.

A further object is to provide a device of the above character which is adapted to be applied to the ordinary corsets fitted with spaced eyelets so that broad ribbon lacings may be used instead of the ordinary lacing. Other objects will appear hereinafter.

The invention is illustrated in the accompanying drawings, in which:

Figure 1 is a front view in perspective of the ribbon receiving member showing it detached and as adapted to be applied to a corset.

Fig. 2 is a rear view in perspective of same.

Fig. 3 is a detail horizontal section illustrating the manner of applying the ribbon receiving member to a corset and attaching it through the eyelets.

Fig. 4 is a view in perspective showing a pair of the ribbon members as detached with fastening means removed and illustrating the manner of connecting the ribbon thereto.

Fig. 5 is a view in perspective illustrating a modified form of the invention showing the ribbon engaging member as formed with a single ribbon receiving slot instead of a pair of slots as shown in Fig. 4 and depicts the manner of lacing the ribbon there-through.

Fig. 6 is a view in perspective of the ribbon engaging member shown in Fig. 5.

Fig. 7 is a view in elevation showing a further modified form of the invention showing it as adapted to be built in the garment and as extending continuously along the edge thereof.

Fig. 8 is a detail section as seen on the line 8—8 of Fig. 7 showing the manner of securing the ribbon engaging member to the garment.

Fig. 9 is a modified form of the device shown in Fig. 7.

In carrying out my invention in the form shown in Figs. 1, 2, 3 and 4, I provide a plate which may be formed of metal or other suitable material having a pair of elongated slots 10 and 11 forming a series of three parallel bars 12, 13 and 14 connected together at their ends by portions 15 and 16. The intermediate bar 13 is preferably offset and spaced a short distance forward of the front faces of the side bars 12 and 14. The portions 15 and 16 are extended and bent rearwardly upon themselves to form inturned flanges 17 and 18 forming hooks adapted to extend over the edge of a garment which flanges are connected together by a bar 19 arranged to be disposed on the inner side of the garment while the bars 12, 13 and 14 extend on the outer side thereof.

As a means for detachably connecting the member just described to an ordinary corset through the eyelets thereof and adapted to engage eyelets of the corset irrespective of different spacing of the eyelets, a series of fasteners 20 are provided and slidably carried on the bar 19. The fasteners are here shown as comprising spring members formed with loops 21 slidably engaging with the bar 19 which members extend rearwardly of the bars 12, 13 and 14 and are bent at their outer ends so as to pass through eyelets 22. Hook shaped terminals 23 are formed on the fasteners to engage the side bar 14 on being passed through an eyelet as shown in Fig. 3. Any suitable means of engagement with the eyelets may be provided as desired. The fasteners being slidably on the bar 19 permit their being spaced in various distances apart according to variations in spacing of the eyelets 22.

While I have shown a pair of fasteners as carried by the rear bar 19 it is obvious that a larger number may be used according to 110

the length of the ribbon receiving member and as occasion may require.

A pair of these ribbon engaging members *a* and *b* are secured to the contiguous edges 5 of the garment at opposite points in the position shown in Fig. 4 and a ribbon 24 is rove through the pair of fasteners as follows: A portion *c* of the ribbon is passed over the bar 14 of member *a* thence down- 10 wardly through slot 11 beneath bars 13 and 12 and between bars 12 and 19 and a portion *d* thence passes to member *b* between bars 12 and 19 and is brought upwardly through slot 10 and returned in portion *e* upon itself 15 over bar 12. Portion *e* is then passed under bar 12 on member *a* and up through slot 10 and returned upon itself over bar 12 in portion *f*. This portion is carried to mem- 20 ber *b* and passed beneath the intermediate bar 13 through slots 10 and 11 and over bar 14 the end portion *g* and the end portion *c* thus extend at opposite directions and are adapted to be carried around the portion of 25 the body on which the garment is worn to be affixed in any desired manner. In the form of the invention shown in Fig. 5 the intermediate bar is dispensed with and a single slot provided through which the ribbon is passed as shown.

30 Where it is desired to apply the fastener to the garment in the course of its manufacture the construction shown in Figs. 7, 8 and 9 may be resorted to in which event the fasteners 20 are dispensed with and the

bar 19 is stitched in the hem of the garment in any suitable manner. Any other fastening means may be employed as occasion may require.

While I have described the invention as particularly adapted for use on corsets it is 40 manifest that it may be employed in any instance where it is desired to use a lacing and while I have shown and described a specific embodiment of the invention such is 45 merely setting forth the form preferred at this time and it is obvious that various changes may be made as occasion may require without departing from the spirit and scope of the invention as set forth in the appended claims.

50 I claim:

1. In a garment lacing, a plurality of bars connected at their ends forming ribbon receiving slots, inturned flanges carried by said bars, a bar carried by said flanges and eyelet engaging slidable fasteners on said last named bar.

2. In a garment lacing, a series of three bars connected at their ends forming ribbon receiving slots on opposite sides of the intermediate bar, a pair of inturned flanges carried by one of the side bars adjacent its ends, a bar connecting the outer ends of said flanges, a series of eyelet engaging fasteners slidable on said last named bars and hooked ends on said fasteners adapted to engage said intermediate bar.

60 JULIA H. AUERBACH.
